(57) **CLAIM**

We claim, the ornamental design for a vibratory roller, as shown and described.

DESCRIPTION

FIG. 1 is a rear right perspective view of a vibratory roller showing our new design;

FIG. 2 is a front left perspective view thereof;

FIG. 3 is a right side view of thereof;

FIG. 4 is a left side view thereof;

FIG. 5 is a top plan view thereof;

FIG. 6 is a rear view thereof; and,

FIG. 7 is a front view thereof.
